UNITED STATES PATENT OFFICE.

LEMUEL BANNISTER, OF PHILADELPHIA, PENNSYLVANIA.

GRATE.

SPECIFICATION forming part of Letters Patent No. 267,737, dated November 21, 1882.

Application filed July 28, 1882. (No model.)

To all whom it may concern:

Be it known that I, LEMUEL BANNISTER, of Philadelphia, Philadelphia county, State of Pennsylvania, have invented certain Improvements in Grates, of which the following is the specification.

My invention relates to that class of furnaces, stoves, grates, &c., where the grate-bars are rocked for the purpose of cleaning or raking the fire; and my invention consists in constructing the bed-plate of the furnace or grate so as to permit the rocking appliances to be applied to stoves of ordinary construction, yet conceal the same, avoid the distorting of the frame or casing of the stove, and cheapen the manufacture, as fully described hereinafter.

In the drawings, Figure 1 is a perspective view of a portable cylinder-stove, with part of the fire-pot and base broken away to illustrate my invention; and Fig. 2 is a transverse section, showing a modification.

It is common in some classes of grates to use rocking bars and appliances connected to the ends of the bars, whereby all may be rotated in unison to rake the fire. As heretofore constructed these appliances, when applied to a stove, are exposed, in many instances detracting from the finish of the article, sometimes presenting projections upon which the clothing can catch, and any attempt to conceal them as constructed would necessarily distort the casing.

My invention consists in so arranging the rocking devices and in so constructing the frame or base of the stove or other articles that such devices shall be mainly below the level of the grate-bars and wholly concealed, without interfering in the least with the operation of the rocker-lever or altering the form of the casing.

In the drawings I have shown my invention in connection with the "Mershon grate," in which each grate-bar *a* is connected to a spindle that projects forward and carries an arm, *c*, all the arms being connected by a cross-bar, *d*, and rocked by a lever, *A*. In place of extending these appliances out beyond the front plate, as heretofore, and turning the crank-arms *c* upward, I turn said cranks downward, as shown, and extend forward beyond the front plate and from the bed-plate a supplemental

plate, *B*, and vertical face-plate, which conceal the arms and cover the raking appliances, as shown.

To permit of the use of the raker-lever or other device, I make a slot, *s*, in the cover-plate at any suitable point. For instance, it may be above the usual eye-lugs, *f g*, as in Fig. 1, the lever being passed through the slot *s* in the plate *B* into said sockets and operating as set forth in Letters Patent heretofore granted to G. B. Mershon. Where a lever is used I prefer to dispense with the eye-lugs *f g* shown in Fig. 1, and to make a lever-socket, *i*, in one of the arms *c*, as shown in Fig. 3. This construction (which is applicable in most cases where such rocking devices are used) reduces the cost of manufacture, insures the simultaneous rocking of all the bars, including the center-bar, and preserves the parts all in their relative positions, while in the old construction illustrated in Fig. 1 the removal of the lever permits the center bar to rotate freely while the others are kept in position.

In place of socketing the arm, it may have a projection on the end adapted to a socket in the end of the lever.

After the lever is removed a plate, *e*, covering an opening in the front plate, may be detached, and the center-bar arm may be drawn forward to permit the center bar to drop. In such case the pin *m*, connecting the arm *c* to the cross-bar *d*, may be so long that the movement of the arm will not detach it from the pin.

The extended plate *B* may be used with different devices for moving the grate-bars with like effect, and said plate may be separate or a part of the usual upper base-plate.

It will be seen that by the construction above set forth the bar-operating devices are kept entirely out of sight until the fire is to be raked, and then the operating lever or bar only is exposed.

I am aware that operating devices have been arranged within the casings of sliding grates and shakers, and do not claim broadly arranging grate-operating devices within the casing; but

I claim—

1. The combination, with a heater, of a series of rocking grate-bars, *a*, with pendent end arms, all connected to one cross-bar, *d*, and all

arranged and connected within the body of the heater, and an external lever, A, whereby all of said arms may be simultaneously vibrated through the medium of the bar d, as set forth.

5 2. The combination, with the rocking bars and their connected arms e, of a detachable lever, A, having a socket or projection corresponding to a socket or projection on one of the arms, for the purpose specified.

In testimony whereof I have signed my name to this specification in the presence of two subscribing witnesses.

LEMUEL BANNISTER.
